(57) **CLAIM**

The ornamental design for a cordless hair straightener comb, as shown and described.

DESCRIPTION

FIG. 1 is a front side perspective view of a cordless hair straightener comb showing my design;

FIG. 2 is a front elevational view thereof;

FIG. 3 is a left side elevational view thereof;

FIG. 4 is a right side elevational view thereof;

FIG. 5 is an enlarged top elevational view thereof;

FIG. 6 is an enlarged bottom elevational view thereof;

FIG. 7 is a rear elevational view thereof;

FIG. 8 is another front side perspective view thereof; and,

FIG. 9 is a rear perspective view thereof.
